UNITED STATES PATENT OFFICE.

HERBERT A. AUSTIN, OF BOSTON, MASSACHUSETTS.

DESIGN FOR A DISPLAY-CABINET.

46,391.

Specification for Design.

Patented Sept. 15, 1914.

Application filed February 15, 1913. Serial No. 748,734. Term of patent 7 years.

To all whom it may concern:

Be it known that I, HERBERT A. AUSTIN, a citizen of the United States, residing in the county of Suffolk, city of Boston, and Commonwealth of Massachusetts, have invented a new, original, and ornamental Design for a Display-Cabinet, of which the following is a specification, reference being had to the accompanying drawing, which forms part of this application.

Figure 1 is a side elevation of a cabinet embodying my design; and Fig. 2 is a cross-section through the central portion of the same, showing parts in vertical elevation.

In the drawings the part 1 is a semi-cylindrical structure of transparent material and has vertical end closures 6 and 7. The bottom portion of the structure is a trough-like receptacle or cradle comprising in its structure making up the design inclined side members 2 and 3 framed and closed together

by vertical end pieces 4 and 5, all the members 2, 3, 4 and 5 being of opaque material contrasting in general appearance with the transparent semi-cylindrical part 1. Suitable supporting portions are provided by the illustrated contour of the end pieces 4 and 5.

As recited above the members described are alone essential for the proper embodiment of my design, the mechanical features of a similar structure being claimed in my co-pending application, Serial No. 748,714, filed Feb. 15, 1913, and forming no part of my claim herein.

I claim:

The ornamental design for a display cabinet as shown and described.

HERBERT A. AUSTIN.
